(57) **CLAIM**

The ornamental design for a knitting needle, as shown and
described.

DESCRIPTION

FIG. 1 is a front view of the new design for a knitting needle,
FIG. 2 is a left side view of FIG. 1,
FIG. 3 is a right side view of FIG. 1,
FIG. 4 is a back view of FIG. 1,
FIG. 5 is a top view of FIG. 1,
FIG. 6 is a bottom view of FIG. 1,
FIG. 7 is a front left perspective view of FIG. 1; and,
FIG. 8 is a back right perspective view of FIG. 1.
The broken lines depict portions of the article that form no
part of the claimed design.

1 Claim, 2 Drawing Sheets

English Translation of the Written Opinion of the International Searching Authority in international application No. PCT/EP2016/070601, dated Oct. 28, 2016.

Applicant disclosure at trade fair. Name of trade fair: h+h cologne. Location of trade fair: Cologne, Germany. Dates of trade fair: Mar. 18, 2016-Mar. 20, 2016. Picture of booth at trade fair is attached.

Applicant distributed brochure at trade fair. Name of trade fair: h+h cologne. Location of trade fair: Cologne, Germany. Dates of trade fair: Mar. 18, 2016-Mar. 20, 2016. Brochure attached.

Applicant showed video at trade fair. Name of trade fair: h+h cologne. Location of trade fair: Cologne, Germany. Dates of trade

fair: Mar. 18, 2016-Mar. 20, 2016. url of video shown at trade fair:

<https://www.youtube.com/watch?v=UFy1PomtxMM&index=14&list=PL3DD0FF876A8ECF3F>.

Applicant created website for trade fair. Name of trade fair: h+h cologne. Location of trade fair: Cologne, Germany. Dates of trade

fair: Mar. 18, 2016-Mar. 20, 2016. url of website: www.prym-ergonomics.com.

Applicant distributed samples to field workers at trade fair. Name of trade fair: h+h cologne. Location of trade fair: Cologne, Germany. Dates of trade fair: Mar. 18, 2016-Mar. 20, 2016.

Applicant sales. Dates of sales: Jan. 2017. Locations sales were made to: Germany, Switzerland, France, Denmark, Netherlands, Finland, Sweden, Italy, United Kingdom, Norway, Austria, Belgium, Luxemburg, Aland.
